UNITED STATES PATENT OFFICE

WINTHROP K. HOWE, OF ROCHESTER, NEW YORK, ASSIGNOR TO GENERAL RAILWAY SIGNAL COMPANY, OF ROCHESTER, NEW YORK

INTERLOCKING SYSTEM FOR RAILROADS

Application filed September 12, 1929. Serial No. 392,138.

This invention relates to power interlocking systems, and more particularly pertains to indication means and devices for such systems.

In power interlocking systems, it is desirable, for reasons familiar to those skilled in the art, to provide indication latch mechanisms for the levers controlling the operation of switches and signals, and to provide suitable means for releasing such an indication latch mechanism for a particular lever when the switch or signal, controlled by that lever, has properly operated or responded. In one type of indication system, to which the present invention more particularly relates, current from a battery or other suitable source located at the switch machine, is controlled by contacts operated by the switch machine and is transmitted to the tower to be employed for actuating the indication latch mechanism.

In the type of indication system above described, sometimes called a constant current or battery type of indication in contrast to the dynamic type of indication, it may happen that an improper or false indication can be given under a certain combination of circumstances. For example, when the operator moves his control lever to a new position, there is a short interval of time, after power is applied to the switch machine, during which the contacts of the switch machine controlling the indication relay remain closed and the indication relay is energized; and if the operator should quickly return the control lever to its former position, the indication latch mechanism may be released, even though the operation of the switch machine from its former position has been initiated. Under such conditions, if provisions are made so that the switch machine will automatically reverse and follow the movement of the control lever to its original position, no particularly unsafe condition results; but, if the switch machine should fail to reverse due to failure of parts, blowing of the fuse by excessive current occurring by such quick reversal of the control lever, or the like, the inertia of the motor armature and the gearing of the switch machine might unlock the track switch

points and even partially move them. This contingency would be unsafe, because the control lever would be in one extreme position, although the track switch would be unlocked and partly moved.

With these considerations in mind, it is proposed in accordance with the present invention, to provide a time element device which is set into operation upon each movement of the control lever to a new operating position to prevent the actuation of the indication latch mechanism for a limited time after each such lever movement, sufficient to assure such operation of the switch machine as will deenergize the indication relay and avoid an improper indication under such conditions above explained.

It is a further object to provide such a time element device coacting with its associated lever in a manner to leave the normal facility of operation unaffected.

In describing the invention in detail, reference will be made to the accompanying drawings, in which like reference characters refer to like objects, and in which:

Fig. 1 is a diagrammatic view of one specific embodiment of the present invention as applied to one type of an electrically operated switch machine having a constant current type of indication system.

Fig. 2 is one modification of the present invention.

Various other objects, purposes and characteristic features of the present invention will be in part obvious and in part pointed out as the description of the invention progresses.

A still further object is to provide an economical control of the switch position repeating relay by the use of superimposed alternating current over the control wires of the switch machine.

With reference to Fig. 1 of the drawings, a track switch TS is shown as operated by a suitable switch machine SM, which is preferably of the type described in my Patent No. 1,436,903, dated September 4, 1923. This switch machine SM has the usual armature A and field winding F, and also associated therewith various groups of contacts.

The contacts included within a dotted rectangle designated PC are known as the pole changer contacts and accomplish the reversibility of the switch machine SM. These pole changing contacts PC include a movable contact block 4 of insulating material upon which are mounted the contacts 5 and 6 making contact between certain pairs of fixed contacts in either the normal or reverse extreme positions, being operated to such positions mechanically by the switch machine at the completion of the corresponding operation; and are operated to an opposite position in midstroke of the switch machine by the energization of a corresponding pair of two pairs of pole changing coils 7 and 8.

The contacts included within a dotted rectangle designate PCC are known as pole changer coil contacts and include a movable contact block 9 of insulating material which furnishes a mounting for the contacts 10 and 11. The pole changer coil contacts PCC include two pairs of fixed contacts, one of said pairs being electrically interconnected when the contact block 9 is in either a normal or reverse position, and both of said pairs being electrically interconnected when the contact block 9 is in an intermediate position. This movable contact block 9 is operated to normal or reverse extreme positions at the end of each corresponding operation of the switch machine SM, and is caused to assume an intermediate position during the operation of the switch machine or any other time that it is unlocked.

The contacts included within a dotted rectangle designated PD are known as point detector contacts and include a movable contact block 12 of insulating material which is caused to assume extreme normal and reverse positions when the track switch is in corresponding positions and locked; but it is caused to assume an intermediate position when the track switch is being operated from one extreme position to another, or at any such time that said track switch is unlocked. Mounted upon the movable contact block 12, there are contacts 13 and 14, which make contact between their respective pairs of fixed contacts when in the normal or reverse extreme positions only; a shunt contact 17 biased toward a contacting position, is actuated to a non-contacting position only when the movable contact block 12 is in a normal position; a similar shunt contact 18 biased toward a contacting position is actuated to a non-contacting position only when the movable contact block 12 is in an extreme reverse position. An example of an operating mechanism of such point detector contacts is disclosed in the patent to C. S. Bushnell, No. 1,517,236, dated November 25, 1924.

Associated with the point detector con-

tacts PD, there is a local transformer T, the primary of which is supplied with potential from a suitable alternating current source over a transmission line extending from the interlocking tower.

In the tower, a control lever L is provided being capable of assuming the usual full normal and full reverse positions indicated by the arrows N and R respectively as they appear opposite an arrow A on the lever L. These full positions of the lever L are supplemented by the normal and reverse indicating positions designated by the arrows NI and RI respectively, which indicating positions are determined by an indication latch mechanism IM including an indication magnet 19 and plunger 20. The movement of the lever L from a full position to an indication position operates a tappet bar 21 to a central position by means of a cam slot 22 in the usual well known manner.

The lever L also governs the operations of the switch machine SM over normal and reverse operating wires N and R respectively in conjunction with a common return wire C, the operating and indicating circuits being completed over these wires by movable contact members 27, 28 and 29 which make contact between certain pairs of fixed contacts when the lever L is in the positions N and NI, and make contact between certain other pairs of fixed contacts when the lever L is in the position R and RI.

A lever lock 23 is provided to lock the lever L against movement from its full normal or full reverse position when the detector track section associated with the track switch TS is shunted. The conditions of this detector track section is repeated by a track repeater relay TR which is controlled by a track relay T at the switch.

Two energy saving contacts 24 and 25 are provided which may be actuated to contacting positions by the control of a lever latch 26.

Associated with the indication latch mechanism IM is an SS relay having a local phase winding 30 continuously energized from a secondary of a local transformer T¹, and having its line phase winding 32 energized over two line wires from the secondary of the local transformer T in accordance with the position and locked condition of the track switch TS. This SS relay has a contact 33 which assumes either of two extreme positions depending upon the relative instantaneous polarity of the currents flowing in the local phase winding 30 and the line phase winding 32, and assumes a deenergized central position when either or both phase windings are deenergized.

A time element device TE is operated by the lever L each time the said lever is moved to a new operating position. This time ele-

- ment device TE is diagrammatically shown as a tooth plunger 42 slidably attached to the frame of the interlocking machine represented by portions 43 and 44 and is biased to a contacting position with the surface of lever L by a spring 45. Attached to this plunger 42 and insulated therefrom is a contact member 46 which electrically interconnects two fixed contacts conventionally shown as arrows. A roller 47 is mounted upon the lower extremity of the plunger 42 to eliminate the contacting friction between the plunger 42 and the surface of the lever L. On the surface of the lever L over which the roller 47 travels, a projecting cam 48 is provided to force the plunger 42 in an upward direction when the lever is moved from a normal operating position to a reverse operating position. This motion is sufficient to move the contact member 46 to a non-contacting position which position is maintained for a predetermined desired period of time by means of an escapement mechanism including a gear 50 which engages with the teeth upon the plunger 42, a shaft 51 connecting the gear 50 with a ratchet gear 52. An escapement wheel 53 is supported upon the same axle 51 in a manner that the ratchet gear 52 may rotate in a clockwise direction freely, but can not rotate in a counter clockwise direction due to the engagement of a spring biased detent 54 being biased by a spring 55. An escapement pawl 56 is provided to prevent the rotation of the escapement wheel 53 in either direction except at a predetermined rate. Thus, when the cam 48 upon the lever L is moved under the roller 47, the motion of the plunger 42 quickly rotates the ratchet gear 52 in a clock-wise direction while the escapement wheel 53 does not appreciably rotate due to the detaining effect of the escapement pawl 56. However, the spring 45 tends to move the plunger 42 in a downward direction as soon as the cam 48 moves away from the roller 47, but it can only do so at a rate determined by the rate at which the escapement wheel 53 may rotate in a counter clockwise direction, as the gear 50, shaft 51 and ratchet gear 52 are not allowed to rotate freely in a counter clock-wise direction, but are caused to rotate synchronously with escapement wheel 53 due to the engagement of detent 54. Thus, the contact member 46 is raised to a non-contacting position each time the lever L is moved from a normal indication position NI to a reverse indication position RI and returns to a contacting position after a predetermined time. It is believed that the usefulness and the operation of such a time element device TE will be more readily understood by further description being given from the standpoint

of the operation of an interlocking system in which such a time element device is included.

Operation of the system

In order to show the coordination of the various devices of an interlocking system including the time element device TE of the present invention, it is considered advisable to consider a complete operation of the system from a normal condition to a reverse condition, with such a description deemed to be sufficient to disclose the present invention, as the operation from the reverse condition to the normal condition is merely an inverse function.

With the apparatus and circuits of the interlocking system in the normal condition as shown, the contact 33 of the SS relay is in a right hand energized position as the local winding 30 is continuously energized and the line phase winding 32 is energized over a normal energizing circuit completed with the track switch TS and switch machine SM in normal locked positions.

The normal energizing circuit for the line phase winding 32 for the relay SS is traced as follows:—from the right hand terminal of the secondary of transformer T, through wires 60 and 61, contacts 62—13, wires 63, 64 and 65, winding 32 of relay SS, wires 66, 67 and 68, contacts 69—14, wires 70 and 71, to the left hand terminal of the secondary of transformer T.

Let us assume that the operator desires to reverse the track switch TS and to do so presses the lever latch 26 preparatory to moving the lever L in a left hand direction. This operation closes the energizing circuits through contacts 25 and 24 for energizing the lock 23 and the indication magnet 19 respectively.

The energizing circuit for the indication magnet 19 is traced as follows:—from a suitable source of electric potential indicated as B+, through closed contact 24, wire 72, contact member 46, wire 73, coils of indication magnet 19, wires 74 and 75, contacts 76—29, wire 77, contact 33 in a right hand position, to the opposite terminal of the suitable source of electrical potential indicated as B-.

Assuming the detector track section governing the relay T to be unoccupied, the energizing circuit for the lock 23 is completed through a circuit traced as follows:—from the positive terminal of a suitable source of potential indicated as B+, through front contact 78, wire 79, closed contact 25, wire 80, winding of magnet 23, to the opposite terminal of the suitable source indicated as B-.

With the electric lock 23 energized, its plunger is moved to such a position that the lever L may be moved in a left hand direction. When the lever L is moved beyond the normal indication position NI, the circuit for the indication magnet 19 is opened at contacts 76, 130

permitting a force drop cam 81 to force the plunger 20 downward into a locking position which prevents movement of the lever L beyond the reverse indicating position RI.

5 During the movement of the lever L from the position NI to the position RI the plunger 42 is actuated to an upper extreme position by the cam 48 which moves the contact member 46 to a non-contacting position, as hereinbefore described.

10 With the lever L in the reverse indicating position RI, the reverse operating circuit for the switch machine SM is completed which causes the switch machine to unlock 15 and operate the track switch to a reverse position and then again lock the switch. This operating circuit for the switch machine SM is traced as follows:— from the positive terminal of a suitable source of electrical potential indicated as B+, through the fuse 49, wire 82, contacts 83—27, wire 84, reverse operating wire R, wire 85, contacts 86—6, wires 87 and 88, armature A, wire 89, contacts 90—5, wires 91 and 92, field winding F, wire 93, through the common wire C to the opposite terminal of the suitable source of electrical potential indicated as B-.

15 As soon as the switch machine armature A has completed a certain number of revolutions to unlock the switch machine SM and track switch TS, the contact block 12 assumes a central position, in which position the alternating current supplied to the line phase winding 32 over a circuit heretofore traced is opened at the contacts 62—13 and 69—14; also the control wires 65 and 66 are shunted by the shunt contacts 17 and 18 through wires 94, shunt contact 17, fixed contact member 95, wire 96, shunt contact 18, fixed contact 97, wires 98 and 67. Thus, the contact 33 of the SS relay is assured of being operated to a central deenergized position.

20 Also, with the switch machine SM unlocked and in operation, the contact block 9 is operated to a central position so that either the pole changer coils 7 of the pole changer coils 8 may be energized according to whether the reverse operating wire R or the normal operating wire N is energized with positive potential. In other words, with the reverse operating wire R energized the coils 7 are energized to hold the contact block 4 in its present position even though the switch machine SM is unlocked, through a circuit including wire 99, contacts 100—10, wire 101, coils 7, wire 102, through the wire C to negative potential. Also, with the contact block 9 in a central position should positive potential be applied to the normal operating wire the pole changer coils 8 would be energized through wire 103, contacts 104—11, wire 105, pole changer coils 8, wire 106, through the wire C to negative potential, to 25 control the contact block 4 to a reverse po-

sition, thus resulting in the reversal of the switch machine armature A.

With the switch machine SM and track switch TS in an unlocked condition, the time element device TE has operated toward its biased position so that the contact member 46 is now in a contacting position. When the switch machine SM and track switch TS reach a reverse position and locked condition which is indicated by the energization of contact 33 of the SS relay to a left hand dotted line position, the indication magnet may be energized controlling the plunger 20 to disengage the lever L, and allowing the operator to control said lever L to its full reverse position R.

30 Assuming that the switch machine SM and track switch TS have operated to reverse positions and locked conditions, the contact blocks 4, 9 and 12 are also operated to reverse extreme positions.

With the contact block 4 in a reverse position, a snubbing circuit for the switch machine SM is completed which dynamically brakes the momentum of the armature A. 35 This dynamic snubbing circuit is traced as follows:— from the upper terminal of armature A, through wires 89 and 113, contacts 114—6, wires 115, normal operating wire N, wire 116, contacts 117—28, wire 118, common wire C, wire 93, field winding F, wires 92 and 118, contacts 119—5, wire 88, to the lower terminal of armature A.

40 With the contact block 12 in a reverse position, the shunt contact 18 is actuated to a non-contacting position, so that with the contacts 13 and 14 in reverse positions, a reverse energizing circuit for the line phase winding 32 for the relay SS is completed, which is traced as follows:— from the right hand terminal of the secondary of transformer T, through wire 60, contacts 107—14, wire 66, line phase winding 32, wires 65, 64 and 108, contacts 109—13, wire 71, to the left hand terminal of the secondary of transformer T.

45 Inasmuch as the instantaneous relative polarity of the line phase winding 32 has been reversed in respect to the instantaneous polarity in the local phase winding 30, the contact 33 assumes a left hand dotted line position. The contact 33 and the contact member 29 are in corresponding positions, so when the operator again presses the lever latch 26 closing the contact 24, the indication magnet 19 is energized inasmuch as the time element device TE is in a normal biased position. This energizing circuit for the indication magnet 19 is traced as follows:— from the positive terminal of suitable source of electrical potential indicated as B+, through closed contact 24, wire 72, closed contact 46, wire 73, coils of indication magnet 19, wires 74 and 110, contacts 111—29, wire 112, contact 33 in a left hand dotted line position, to

the opposite terminal of the suitable source indicated as B-. The plunger 20 is now operated to a disengaging position in respect to lever L, so that the lever may be moved to 5 its full reverse position R.

One operation of the specific interlocking system, including the time element device of the present invention, has been shown and described. It is obvious that the normal operation of the system is not in any manner retarded or hindered from completing its normal operating functions due to the incorporation of the time element device within the system. However, in order to make 10 clear the usefulness of such a time element device, the case or combination of circumstances, in which such a device is made necessary, will now be considered.

Referring to the operation of the lever L from the normal position N to the reverse position R just described, let us assume that the lever L has been moved to the reverse indication position RI, and the operator changes his mind and tries to quickly change 15 the lever L to its normal position N. Such a movement of the lever L can not be accomplished as the movement of the contact member 46 to a non-contacting position prevents the energization of the indication magnet 19, thus preventing the release of the indication 20 latch mechanism IM which prevents the movement of the lever L from being moved to a full position.

Let us assume, that the time element contact 46 is not in place and the wires 72 and 73 are permanently connected together. Then the lever L upon being quickly returned to its normal indicating position NI will have given the armature A a chance to make several revolutions while said lever L was still in the reverse indicating position RI. Then, with energy now upon the normal control wire N, the pole changing coils 8 are energized moving the contact block 4 to a reverse 30 position, so that the armature A will start revolving in an opposite direction if the fuse F does not blow out. However, due to the lack of a counter electromotive force within the motor, a sudden inrush of current occurs 35 and is likely to blow the fuse F. Assuming that the fuse F does blow out and the armature A continues rotation due to its inertia and the momentum of the switch machine gearing, then the contact 33 would still be 40 in a normal energized position as the switch machine is not unlocked when the lever L is reversed. Thus, the normal energizing circuit for the indication magnet 19 is completed, allowing the lever L to be returned to 45 its full normal position N, but the momentum of the motor continues to operate the switch machine SM to an unlocked condition. Should a train now pass over the 50 track switch TS the vibration might be sufficient to cause the switch points to slightly

open, so that a flange of a car wheel might become engaged with the open point and cause the train to split the switch.

From the foregoing description, it is seen that the possibility of a false or "hang over" indication of an interlocking system without the time element device of the present invention, is due to a time interval during which the indication relay contacts indicate the true position of the switch, and during which an abnormal condition can be set up without such abnormal condition being detected until it cannot be remedied. By way of further explanation, let us assume that the time interval existing between the initiation of rotation of the motor armature and the unlocking of the track switch equals unity. Also, let us assume that the momentum of the motor armature and switch machine gearing will cause further operation for one-half unit of time after power is cut off. Then, if the operator returns the control lever to a former position when three-fourths of this first unit of time has elapsed and the fuse blow out, the control lever may be returned to the full position although the switch machine continues to move for one-half unit of time, thus unlocking the track switch. Obviously the SS relay cannot indicate the track switch as unlocked until the condition exists.

Should a switch machine be so constructed as to be able to stop immediately as soon as its power supply is removed, the condition might arise in which the power cut-out might open the circuit just as the track switch is unlocked with the control lever reaching its former position at the same instant. Such a condition would still be undesirable.

However, the present invention provides a true compensation for such conditions, in that a time element is used to counter-act an undesirable time element.

It is obvious from the above description, that the time element device of the present invention may be varied to operate through a period of time in accordance with the conditions to be met in practice, which period of time for the specific case stated above is preferably slightly greater than the time required for the switch machine to unlock the track switch.

Other means have been proposed for use in battery type indication systems, such as a quick acting switch which selects the circuit for the opposite or next indication when the control lever is moved from the other or its last indicating position to its corresponding full position. Such a device prevents the returning of the control lever to its former position until after the originally intended operation of the lever is completed. The interlocking system of the present invention gives no such undesirable results.

With reference to Fig. 2 of the drawings, a modification of the SS relay control is shown,

which provides an economical means of accomplishing such control. The devices in Fig. 2 which are similar to devices in Fig. 1 have been shown with the same reference characters having distinctive exponents. In other words, the devices in Fig. 2 which have the same reference characters with distinctive exponents, are the same devices included in another circuit arrangement according to the invention and are operatively associated with the lever L and the time element device TE.

The point detector contacts PD^a control the supply of alternating current potential to the primary winding of a transformer T^a, with the secondary of this transformer connected in series with the common wire C^a. Thus, with the line phase winding 32^a of the relay SS^a connected in series in the wire 118 (see Fig. 1) which completes the snubbing circuit, a circuit arrangement is provided so that the SS relay may be controlled over the last snubbing circuit of the switch machine motor.

25 A resistance 120 is provided in the primary circuit of the transformer T^a to limit the effect in the primary winding of the surge of the dynamic current flowing in the secondary winding. A condenser 121 is shunted across the field winding F^a.

Movable contacts 13^a and 14^a are controlled in the same manner as explained for Fig. 1 to make contact between certain pairs of fixed contacts in order to provide the reversal of 35 instantaneous polarity upon the primary of the transformer T^a as is obvious from the drawings. Likewise, the pole changer contacts PC^a and the pole changer coil contacts PCC^a are controlled in a similar manner as 40 heretofore explained.

When the track switch TS and switch machine SM are in their normal locked positions, contacts 13^a and 14^a are in the position, as shown, thus energizing the transformer T^a. 45 With these conditions obtaining, alternating current is superimposed upon the snubbing circuit of the switch machine, energizing the line phase winding 32^a of the relay SS^a through a circuit traced as follows:— from the right hand terminal of the secondary of transformer T^a, through common wire C^a, field winding F^a and condenser 121 in multiple, wires 151 and 152, contacts 90^a—5^a, wire 153, armature A^a, wires 154 and 155, contacts 55 86^a—6^a, wire 156, reverse operating wire R^a, contacts 157^a—28^a, wires 158 and 159, winding 32^a of relay SS^a, wire 160, common wire C^a, to the left hand terminal of the secondary of transformer T^a.

60 During the operation of the switch machine SM, the contacts 13^a and 14^a assume a central non-contacting position, thus deenergizing the transformer T^a. When the control lever L is moved to the reverse position the energizing circuit for the line phase winding 32^a

is also broken at the controller contact 28^a and is not again completed until the track switch TS has operated the point detector contacts PD^a to their reverse positions, the pole changer contacts PC^a and the pole changer coil contacts PCC^a to their reverse positions in correspondence with the controller contacts of the control lever L. At such time, a reverse energizing circuit for the line phase winding 32^a is completed, which is traced as follows:— from the right hand terminal of the secondary of transformer T^a, through common wire C^a, field winding F^a and condenser 121 is multiple, wires 151 and 161, contacts 119^a—5^a, wire 154, armature A^a, wires 153 and 162, contacts 114^a—6^a, wire 163, normal operating wire N^a, wire 164, contacts 117^a—28^a, wire 159, winding 32^a of relay SS^a, wire 160, common wire C^a, to the left hand terminal of the secondary of transformer T^a.

A contact 33^a is operated to its normal position, as shown, when the normal energizing circuit for the line phase winding 32^a is completed, and is energized to a left hand dotted line position, when the reverse energizing circuit is completed, thus controlling circuits as heretofore explained.

It is to be noted that the condensers 121 may be omitted in such cases where it is possible to use a comparatively high secondary voltage on the transformer T^a.

Thus, an interlocking system of the constant current or battery type indication system has been shown and described as providing adequate indication control under the various exigencies of operating conditions. Also, an economical means of accomplishing such control has been included as one modification of the interlocking system of the present invention.

One specific construction of devices and arrangement of circuits, designed for use in connection with one particular type of interlocking system, has been shown; however, it is to be understood that the various devices and circuit arrangements selected are to facilitate the disclosure and nature of the invention rather than its specific form, and it is to be further understood that various modifications and adaptations may be made without departing from the spirit or scope of the present invention as demanded by the following claims.

Having described my invention, I now claim:—

1. In an interlocking system of the type shown and described, a control lever operatively governing the movement of a switch machine, an indication latch mechanism associated with said control lever, indication means capable of actuating said indication latch mechanism when said control lever and said switch machine are in correspondence, and a time element device operably preventing actuation of said indication latch mech-

anism by said indication means for a predetermined time after each governing operation of said control lever.

2. In an interlocking system of the type shown and described, a control lever operatively governing the movement of a switch machine, an indication latch mechanism associated with said control lever, indication means capable of actuating said indication latch mechanism when said control lever and said switch machine are in correspondence, and a time element device including, a normally closed contact operably actuated to a non-contacting position during each governing operation of said control lever, and means operably preventing the return of said contact to a normally closed position until a predetermined time after actuation, with said time element device preventing said indication means from actuating said indication latch mechanism for a certain time after each governing operation of said lever.

3. In an interlocking system of the type shown and described; a control lever operatively governing the movement of a switch machine; an indication latch mechanism associated with said control lever; indication means capable of actuating said indication latch mechanism when said control lever and said switch machine are in correspondence; and a time element device comprising, a contact normally biased to a contacting position, actuating means operably moving said contact to a non-contacting position upon each governing movement of said control lever, and means actively preventing the return of said contact to a normally biased position until after a predetermined lapse of time; whereby said indication latch mechanism is prevented from actuation for a predetermined time interval after each governing movement of said control lever.

4. In an interlocking system of the type shown and described; a control lever operatively governing the movement of a switch machine; an indication latch mechanism associated with said control lever; indication means capable of actuating said indication latch mechanism when said control lever and said switch machine are in correspondence; and a time element device comprising, a contact normally biased to a contacting position, actuating means operably moving said contact to a non-contacting position upon each governing movement of said control lever; and timing means including, an escapement wheel, a one way ratchet connecting said actuating means and said escapement wheel, and an escapement pawl regulating the rate of rotation of said escapement wheel, whereby said timing means actively prevents the return of said contact to its normally biased position until after a predetermined time.

5. In an interlocking system for railroads, a control lever operably controlling a distant

switch machine to either of two extreme positions when in either of two operating positions and operably releasing interlocking means when in either of two extreme positions progressively attained from a corresponding one of said operating positions, an indication latch mechanism preventing movement of said control lever from a particular operating position to a corresponding extreme position except when actuated, said mechanism normally being capable of being actuated when said control lever and said switch machine are in correspondence, and time measuring means for preventing actuation of said indication latch mechanism after movement of said control lever from one operating position to another operating position until after the lapse of a predetermined time interval.

6. In an interlocking system for railroads, a lever controlling a distant switch machine and capable of assuming either a normal position, a normal indication position, a reverse indication position or a reverse position, and means preventing manipulation of said lever from either normal or reverse indication positions to normal or reverse positions respectively except upon indication that said switch machine is in a corresponding position with said lever, said means including, an indication magnet, a switch repeating relay controlling said indication magnet, and time measuring means preventing said indication magnet from being controlled prematurely.

7. In an interlocking system for railroads; a lever controlling a distant switch machine and being capable of assuming either a normal position, a normal indication position, a reverse indication position or a reverse position, and means for preventing manipulation of said lever from either a normal or reverse indicating position to normal or reverse positions respectively except upon indication that said switch machine is in a corresponding position with said lever, said means including an indication magnet, a switch repeating relay; and time measuring means for compensating for the delay in response of said switch repeating relay to the condition of said switch machine.

8. In an interlocking system for railroads, a lever controlling a distant switch machine and being capable of assuming either a normal position, a normal indication position, a reverse indication position or a reverse position, and means comprising an indication magnet for preventing manipulation of said lever from either normal or reverse indicating positions to normal or reverse positions respectively except upon indication that said switch machine is in a corresponding position with said lever, with said means including, a switch repeating relay, a time element contact opened by movement of said lever

- from either the normal or reverse indication position, to the opposite indication position and closed in a predetermined time thereafter, controller contacts controlled by said lever, said indication magnet being controlled by said switch repeating relay in conjunction with said time element contact and said controller contacts.
9. In an interlocking system for railroads, a control lever capable of assuming any one of two extreme or two intermediate positions and controlling a distant switch machine, and means for preventing said control lever from being moved from a particular intermediate position to either extreme position except when said switch machine has completed its operation in correspondence with said particular intermediate position, said means including, an indication magnet, a switch position repeating relay, contacts controlled by said control lever, and a time element contact opened by certain movements of said control lever and closing a predetermined time thereafter, whereby said indication magnet cannot be energized after movement of said control lever until sufficient time has elapsed to allow said switch machine to assume a position in correspondence with said control lever.
10. In an interlocking system for railroads, a control lever capable of assuming any one of two extreme positions, or any one of two intermediate positions and controlling a distant switch machine, an indication latch mechanism preventing movement of said control lever from a particular intermediate position to either extreme position, electro-responsive means for operating said latch when said switch machine and said lever assume corresponding positions, and means preventing actuation of said indication latch mechanism by said electro-responsive means after movement of said control lever from one intermediate position to another intermediate position until after the lapse of a certain predetermined time interval, whereby said control lever cannot be operated out of correspondence with said distant switch machine.
11. In an interlocking system for railroads, a control lever capable of assuming any one of two extreme positions, or any one of two intermediate positions for controlling a distant switch machine, an indication latch mechanism for preventing said control lever being moved from a particular intermediate position to a corresponding extreme position unless said control lever and said distant switch machine are in correspondence, and means preventing actuation of said indication latch mechanism after movement of said control lever from corresponding extreme or intermediate positions to opposite extreme or intermediate positions until after the lapse of a certain predetermined time interval, with said means including a time element contact which is comparatively quickly opened, and requires a time interval for closing.
12. In an interlocking system for railroads, a control lever capable of assuming any one of two extreme positions or any one of two intermediate positions and controlling a distant switch machine, an indication latch mechanism preventing said control lever from being moved from a particular intermediate position to a particular corresponding extreme position except after being energized, with said indication latch mechanism normally being capable of being energized when said control lever and said distant switch machine are in correspondence, and means preventing energization of said indication latch mechanism after movement of said control lever from positions in correspondence with said switch machine to positions out of correspondence with said switch machine until after a certain predetermined time interval, with said means including a time element contact, means for instantaneously opening said time element contact operable by movement of said lever, and means operable for slowly closing said time element contact including an escapement pawl.
13. In an interlocking system for railroads, a control lever capable of assuming any one of two extreme positions or any one of two intermediate positions and controlling a distant switch machine, an indication latch mechanism preventing said control lever from being moved from a particular intermediate position to a corresponding extreme position except after being energized, with said mechanism normally being capable of being energized when said control lever and said distant switch machine are in correspondence, and means preventing energization of said indication latch mechanism after movement of said control lever from one intermediate position to another intermediate position until after a certain predetermined time interval, with said means including, a time element contact, means for instantaneously opening said time element contact including, a reciprocating plunger, and a one-way ratchet, and means allowing said time element contact to close after a predetermined time including an escapement pawl.
14. In an interlocking system, a track switch operated by a switch machine, a control lever governing the operations of said switch machine, an indication latch mechanism preventing extreme movements of said control lever except when actuated, indication means including, point detector contacts operated by said track switch and said switch machine, an electro-responsive device indicating the position of said track switch, two line wires over which said electro-responsive device is controlled in accordance with said

point detector contacts, with said indication means capable of actuating said indication latch mechanism when said track switch and said switch machine are in correspondence 5 with said control lever and locked, and a time element mechanism operably preventing said indication means from actuating said indication latch mechanism during operation of said switch machine before said track switch 10 is unlocked.

15. In an interlocking system, a track switch operated by a switch machine, a control lever governing the operations of said switch machine, an indication latch mechanism preventing extreme movements of said control lever except when actuated, indication means including, point detector contacts operated by said track switch and said switch machine, an electro-responsive device indicating the position of said track switch, means operably controlling said electro-responsive device over the control wires of said switch machine in accordance with said point detector contacts, with said indication means 25 capable of actuating said indication latch mechanism when said track switch and said switch machine are in correspondence with said control lever and locked, and a time element mechanism operably preventing said 30 indication means from actuating said indication latch mechanism during operation of said switch machine before said track switch is unlocked.

16. In an interlocking system for railroads, 35 a track switch, a switch machine for operating said track switch, a control lever, two control wires and a common return wire between said switch machine and said control lever providing normal and reverse operating circuits for said switch machine, and means for indicating the condition of said switch machine operable by alternating current flowing in reverse and normal indicating circuits respectively including said operating circuits 45 of said switch machine.

17. In an interlocking system for railroads, a track switch, a switch machine for operating said track switch, a control lever, two control wires and a common return wire 50 between said switch machine and said control lever providing normal and reverse operating circuits for said switch machine, an electro-responsive device in the tower indicating the position of said track switch and having normal and reverse energizing circuits including said operating circuits of said switch machine, means for energizing said electro-responsive device including, a secondary winding of a transformer in series with said 55 common wire, a condenser for decreasing the reactance of said energizing circuits, and means for controlling the energization of the primary winding of said transformer in accordance with the condition of said track switch.

18. In an interlocking system for railroads, a track switch, a switch machine for operating said track switch, a control lever, two control wires and a common return wire between said switch machine and said control lever providing normal and reverse operating circuits for said switch machine, a secondary winding of a transformer included in series with said common wire, contact means controlling the energization of the primary winding of said transformer in accordance with the conditions of said track switch and said switch machine, and a three position relay in the tower operably controlled by the energization of said secondary winding of said transformer over normal and reverse energizing circuits including said normal and reverse operating circuits of said switch machine, whereby the condition of said track switch is indicated in the tower.

19. In an interlocking system for railroads, a control lever capable of assuming any one of two extreme positions or any one of two intermediate positions and controlling a distant switch machine, an indication latch mechanism when deenergized preventing said control lever from being moved from a particular intermediate position to a particular corresponding extreme position, said indication latch mechanism normally being capable of being energized when said control lever and said distant switch machine are in correspondence, and means preventing energization of said indication latch mechanism after movement of said control lever from positions in correspondence with said switch machine to positions out of correspondence with said switch machine until after the lapse of a certain predetermined time interval, said means including a time element contact,

40 means for instantaneously opening said time element contact operable by movement of said lever, and means operable for slowly closing said time element contact including an escapement pawl.

20. In an interlocking system for railroads, a control lever capable of assuming any one of two extreme positions or any one of two intermediate positions and controlling a distant switch machine, an indication latch mechanism for, when energized, preventing said control lever from being moved from a particular intermediate position to a corresponding extreme position, said mechanism normally being capable of being energized when said control lever and said distant switch machine are in correspondence, and means for preventing energization of said indication latch mechanism after movement of said control lever from one intermediate position to another intermediate position until after the lapse of a certain predetermined time interval, said means including, a time element contact, means for

5 instantaneously opening said time element contact including, a reciprocating plunger, and a one-way ratchet, and means allowing said time element contact to close after a predetermined time including an escapement pawl.

10 21. In an interlocking system for railroads, the combination with a distant switch machine including an electric motor and a local lever, two control wires each used separately in a circuit with a common return wire for operating said switch machine in opposite directions each circuit of which is established so long as said lever and switch machine are 15 out of correspondence, an indicating relay associated with said lever, two indicating circuits each including a different control wire and said common wire and completed only when said lever and switch machine assume corresponding positions, said indicating circuits including means for bypassing said motor to the flow of indicating current distinctive in character from the current used for operating said motor.

20 22. In an interlocking system for railroads, the combination with a distant switch machine including an electric motor and a local lever, two control wires each used separately in a circuit with a common return wire for operating said switch machine in opposite directions each circuit of which is established so long as said lever and switch machine are 25 out of correspondence, an indicating relay associated with said lever and responsive only to current distinctive from the current used for operating said motor, two indicating circuits each including a different control wire and said common wire and completed only when said lever and switch machine assume corresponding positions, said indicating circuits including means for bypassing said motor to the flow of said distinctive indicating current, and means for impressing on said indicating circuits said distinctive currents of distinctive instantaneous polarity corresponding to the 30 position of the switch machine.

35 23. In an interlocking system for railroads, a track switch, a switch machine for operating said track switch, a control lever operable to normal and reverse governing positions for governing said switch machine to normal or reverse positions respectively, indication means for indicating the position 40 of said track switch, electroresponsive means governed by said indication means, and time measuring means initiated by each operation of said control lever for preventing during a predetermined time thereafter the governing 45 of said electroresponsive means by said indication means.

50 24. In an interlocking system for railroads, a track switch, a switch machine for operating said track switch, a control lever operable to normal and reverse governing 55

60 positions for governing said switch machine to normal or reverse positions respectively, indication means for indicating the position of said track switch, electroresponsive means governed by said indication means, time measuring means initiated by each operation of said control lever for preventing during a predetermined time thereafter the governing 65 of said electroresponsive means by said indication means, said time measuring means including, a time element contact, means for instantaneously opening said time element contact including, a reciprocating plunger, and a one-way ratchet, and means allowing said time element contact to close after a predetermined time said means including an escapement pawl.

70 25. In an interlocking system for railroads, a track switch, a switch machine for operating said track switch, a control lever operable to normal and reverse positions for governing said switch machine, a three-position relay for indicating the position and locked condition of said track switch, electroresponsive means having the energization of its windings governed by said three-position relay, and time measuring means initiated by movement of said control lever for preventing for a predetermined time thereafter the energization of said electroresponsive means 75 by said three-position relay.

80 26. In an interlocking system for railroads; a switch machine; a lever for controlling said switch machine, said lever being capable of assuming either a normal extreme 85 position, a normal indication position, a reverse indication position or a reverse extreme position, with said positions being progressively attained; and means allowing manipulation of said lever from normal or reverse indication positions to corresponding normal or reverse extreme positions only when said lever has been in a particular indication position for a predetermined period of time and said switch machine is in correspondence 90 with therewith.

95 In testimony whereof I affix my signature.

WINTHROP K. HOWE.
